UNITED STATES PATENT OFFICE

HERBERT S. JANDUS, OF DETROIT, MICHIGAN, ASSIGNOR, BY MESNE ASSIGNMENTS,
TO GENERAL SPRING BUMPER CORPORATION, A CORPORATION OF MICHIGAN

DESIGN FOR A BUMPER

Application filed July 28, 1927. Serial No. 22,917. Term of patent 3½ years.

To all whom it may concern:

Be it known that I, HERBERT S. JANDUS, a citizen of the United States, residing at Detroit, in the county of Wayne and State of Michigan, have invented a new, original, and ornamental Design for Bumpers, of which the following is a specification, reference being had to the accompanying drawing, forming part thereof, wherein

Fig. 1 represents a plan view and Fig. 2 a

front elevation of a bumper exhibiting my new design. My invention relates to the impact sections of a vehicle bumper and the support means used therewith are shown in dotted lines.

I claim:—

The ornamental design for a bumper substantially as shown and described.

HERBERT S. JANDUS.
